UNITED STATES PATENT OFFICE.

FRANK KOENIGKRAMER, OF CINCINNATI, OHIO.

TREATING-TABLE.

1,286,027.

Specification of Letters Patent. Patented Nov. 26, 1918.

Application filed March 23, 1914. Serial No. 826,503.

To all whom it may concern:

Be it known that I, FRANK KOENIGKRAMER, a citizen of the United States, residing at Cincinnati, in the county of Hamilton and State of Ohio, have invented certain new and useful Improvements in Treating-Tables, of which the following is a specification.

My invention relates to improvements in treating tables. One of its objects is to provide an improved vertically adjustable table, the respective top sections of which are independently supported and adjustable upon the vertically adjustable section of its supporting column. Another object is to provide a table having independently movable and adjustable top sections and improved mechanism to movably support and adjust the respective top sections. Another object is to provide a table having a top section with a variety of different movements, and means to enable said several movements to be employed separately or conjointly. Another object is to provide a table having a movable section yieldingly supported upon a vertically adjustable standard and improved means to vary and adjust the tension thereof. Another object is to provide improved means to tension and limit the movements of the movable top sections to restrain or to prevent excessive or too free a movement thereof. My invention also comprises certain details of form, combination, and arrangement all of which will be fully set forth in the description of the accompanying drawings in which:

Figure 1 is a top plan view of my improved table.

Fig. 2 is a side elevation thereof.

Fig. 3 is a bottom plan view of one of the table top sections and its supporting and adjusting mechanism detached.

Fig. 4 is a sectional detail on line $\alpha\alpha$ of Fig. 3.

Fig. 5 is a sectional detail on line $\nu\nu$ of Fig. 3.

Fig. 6 is a perspective view of one of the tensioning spring shackles detached.

Fig. 7 is a sectional detail of the mechanism employed to support and raise or lower section E of the table top.

Fig. 8 is a view similar to Fig. 7 illustrating a modification thereof.

Fig. 9 is a sectional detail, taken on line t of Fig. 2, of the frame.

Fig. 10 and Fig. 11 are bottom plan views of the table top section D.

Fig. 12 is a sectional detail on line $z z$ of Fig. 11.

Fig. 13 is a sectional detail taken on line $\nu\nu$ of Fig. 1.

Fig. 14 is a perspective view of the bracket 48 detached.

Fig. 15 is a perspective view of the bracket 44 detached.

Fig. 16 is a sectional detail on line $w w$ of Fig. 2.

Fig. 17 is a top plan of the head F and parts mounted thereon.

The accompanying illustrations represent the preferred embodiment of my invention in which A represents a base, having extensions a . B a column vertically adjustable relative to said base, and C, D, and E independent table top sections each supported upon and adjustable relative to said column B.

The column B may be adjusted relative to the base A in any desired manner. I have illustrated said column as a piston seated in a vertical cylinder in the base A, relative to which it is vertically adjustable hydraulically by reciprocating the handle, 2 of a hydraulic pump contained within said piston. A brake shoe 3 forced against the outer face of the piston by means of a set screw 4 threaded through an ear of the base A serves to rigidly lock the piston in its adjusted position to retain the piston in place for long periods.

At the upper end of the piston B is an extended or enlarged head F having a depending arm 5 which is bored to receive a vertical shaft 6, and is provided with a rectangular bar 7 which seats in a corresponding groove in the side of the base A to prevent the column B and head F from turning or rotating relative to the base A. At the upper end of the shaft 6 is a head or block 8 rigidly locked to said shaft and resting upon the upper face of the head F. At the lower end shaft 6 is provided with a collar 9 held in place by a set screw 10 threaded through an ear 11 of the arm 5 and into said collar and in position for the point of said set screw to selectively engage one or more holes in said shaft 6 to lock the shaft to adjusted position and against rotation. Below the collar 9 is a block or collar 12 rigidly locked to shaft 6 by a set screw.

The table top section C is designed to support the head and shoulders of the patient, and is pivotally attached upon a horizontal axis at 14 on opposite sides to arms 15 of the head F. Bars 16 are attached to a projection 17 of the head F and extend outwardly parallel to each other beneath the section C. At the outer end of said bars 16 is a pivotally supported gripping head or stirrup 18 which 5 has a recess through which passes a bar 19 which is hinged at 20 to the under side of the section C. The bar 19 has stops 21 to limit its movement through the stirrup 18 and said stirrup has a block of hardened steel 22 10 which tends by the gravity action of the stirrup 18 to automatically grip the bar 19 and prevent it from passing downwardly through the stirrup. If desired a spring 24 may be employed instead of relying upon 15 gravity to cause the stirrup to grip the bar 19. The bar 19 moves freely in the opposite direction through the stirrup. I also preferably provide a series of perforations in the bar 19 set at regular intervals apart, and 20 by means of which and a pin inserted through one of said perforations above the block 22 said bar 19 may be permanently locked to any desired position. For ordinary 25 adjustments of the section C upon its centers 30 14, the operator may lift the outer end of section C to any desired position of inclination when the block 22 will automatically grip the bar 19 and hold the section in place, or if it is desired to move section C to a position 35 of less inclination the operator takes a hold of the outer end of section C with both hands and by pressing on the lever 25 of the stirrup with his knee releases the engagement of block 22 with bar 19 40 and lowers the section C to the desired position when the block 22 automatically re-engages bar 19.

The table top section D is designed to support the hips of the patient and to have a 45 pivotal movement upon a vertical axis or pin 29, and also to be inclined or tilted upon a horizontal axis approximately above and intersecting said vertical axis, whereby said section D may be adjusted and held to either 50 a horizontal or an inclined position. The section D has downwardly projecting ears 27 by means of which it is pivoted upon a horizontal axis to the frame 28. The frame 28 has a downwardly projecting pin 29 which 55 seats in a recess bored in the upper end of shaft 6. The under face of frame 28 rests upon the head 8 adjacent to the pin 29, and the arm 30 of frame 28 rides so close to the projecting end 31 of head 8 as to engage 60 therewith when section D is subjected to a heavy weight, thereby preventing the pin 29 being bent or unduly strained.

A crank shaft 32 is journaled to the frame 28 with one end 33, projecting to be grasped 65 by the operator while the crank pin 34 at the

other end of shaft 32 engages and travels in a slot 35 formed between the angle plate 36 and the flat plate 37. Said plates are held in position to the under side of section D by means of screws 38 on the shanks of which 70 are springs 39 which yieldingly hold the plate 37 in engagement with the crank pin 34. In the position of the crank indicated in Fig. 11 and in full line Fig. 12 the section D is inclined, while in the position Fig. 10 75 and dotted lines Fig. 12 the section D is in a horizontal position. There is sufficient frictional engagement between the plates 36 and 37 and crank pin 34 to cause the shaft 32 to retain whichever position it is adjusted to. 80

The table top section E is supported upon a frame 40 relative to which it is adjustable endwise, and also pivotally with the axis of its adjusting screw as a center. The frame 40 is pivotally supported upon a horizontal axis at 41 relative to the head 8 and yieldingly tensioned so as to secure a reciprocating or rocking motion of the section E about said axis 41. A screw threaded rod 42 is journaled in brackets 43 and 44 attached to the section E and engages the central threaded boss of the cross bar 45 of the frame 40 to feed the section longitudinally of the frame 40, said screw being rotated by hand by means of the crank 46. A shaft 47 concentric 95 with the screw rod 42 is journaled at one end in the bracket 44 and at the opposite end in a bracket 48 also attached to the section E. Cross bars 49 and 50 are rigidly secured by set screws to the shaft 47 between the brackets 100 44 and 48 so as to rock with said shaft in its bearings. The longitudinal rods of frame 40 pass through eyes in the cross bars 49 and 50 and slide longitudinally therein when the section E is adjusted by the screw rod 42. 105 Rubber buffers or stops 51, carried by bracket 48, engage the ends of the cross bar 50 and noiselessly limit the rocking movement of the shaft 47. The bracket 44 is provided with an annular projection 52 which is 110 engaged by a shoe 53 held in engagement therewith by a set screw 54 carried by the cross bar 49, said shoe serving to prevent the shaft 47 from rocking too freely in its bearings, which action may be varied by adjusting the set screw 54. A hand lever 55 is pivotally attached to section E at 56 and is provided with projecting arms 57 which may be shifted into and out of engagement with the cross bar 49 to lock the section E to a 115 horizontal position above and relative to the frame 40, by preventing rocking motion of the shaft 47 and its cross bars 49 and 50.

The rotary movement of the shaft 6 in its bearing 5 provides for swinging the section 120 E in horizontal planes backward and forward, and this movement is preferably limited and said section returned automatically to a central or normal position by means of a spring 60 attached at one end to a link 64 125 130

pivoted to the projection 31 of the head 8 and at the opposite end to a threaded eye-bar 61 adjustably connected by a nut 62 to a bracket 63 attached to the projection 17 of 5 the head F, whereby any desired tension on spring 60 may be secured.

In order to adjustably tension the movement of the table section E and its frame 40 upon the center 41, and to lock said section E against movement upon said section I provide a frame 68 substantially parallel 10 with frame 40 and pivotally attached at 66 to the collar 12 carried by the shaft 6. A spring shackle 67 is pivoted to a carriage 68 which rides on the frame 65, and is adjustable thereon by means of the screw rod 69. The screw rod is rotatably mounted in a block 70 pivotally attached at 70' to the side bars of frame 65, and is adjusted by means 15 of a hand wheel or crank 71. Another spring shackle 72 is pivotally attached at 73 to the head 8. Said spring shackles, see Fig. 6, are provided with a plurality of eyes to be engaged by a plurality of coiled 20 springs 74 which springs tend to pull the frame 65 upwardly toward the frame 40. A threaded eye-bar 75 is pivoted upon a cross rod 76 of the frame 40, and a nut 77 threaded thereto engages a tube 78, see Fig. 25 7, which tube has forked arms 79 at its lower end pivotally connected to the center 70' of frame 65, thereby enabling the nut 77 to be adjusted to force the frames 40 and 65 apart against the action of the springs 30 74, and also serving to transmit the tension of springs 74 into force tending to lift and support the frame 40 and parts carried thereby. Downward movement of the nut 77 on the bar 75 tends to lift the outer end 35 of section E to a higher point, or to elongate the springs 74, so that adjustment of the nut 77 may be made to substantially counterbalance variable weights to be supported by the section E. The movement of the 40 carriage 68 to or from the base A also serves to increase or diminish the tension of the springs and to increase the leverage of the springs 74 tending to lift the frame 65, and through the rod 75 the frame 40 45 and section E, thus providing an increased range of counterweighting support for the section E.

As illustrated in Fig. 7 the lower end of rod 75 is guided in the tube 78, with the 50 nut 77 and tube 78 only in a thrust engagement leaving the section E free to be lifted still farther by hand with the nut 77 out of contact with the tube 78. In the modification Fig. 8, however, an inner sleeve 80 55 is rotatably mounted in the tube 78' and the rod 75' is threaded to said sleeve 80, which may be turned by its hand wheel 81 to feed the rod up or down within the sleeve 80, while the nut 82 is employed as a stop 60 or lock nut.

In order to lock the section E against pivotal movement upon the center 41 I provide a depending arm 90 which is pivoted upon a cross-bar 19 of frame 40 and its lower end interposed between one of the 70 bars of frame 65 and a strap 92 locked at one end to said bar 65 upon the bolt 70'. At the opposite end the strap 92 is seated over a threaded stud 93, which is fitted with a clamping nut 94, by means of which the 75 free end of arm 90 is clamped to frame 65 to lock section E in place. When unlocked the arm 90 slides freely up and down between the frame 65 and strap 92.

When the supporting members 75, 77, 80 and 78 illustrated in Fig. 7 are employed in connection with the locking member 90 to transmit the resilient strain of spring 74 from the arm 65 to the auxiliary top section E, the member 90 forms a non-extensible connection between members 40 and 65, and hence with members 40, 65, and 6, forms a rectangular frame-work, which prevents the top E and arm 65 from rising above a predetermined position, depending 85 upon the point at which member 90 is clamped to member 65. If however force downwardly is applied to the top E, sufficient to overcome the tension of spring 74, which is variable by adjustment; the force 90 will be transmitted from the top E through member 90 to arm 65, the members 75 and 77 will separate telescopically from member 78 sufficiently to enable the top E and arm 65 to be yieldingly depressed to a limited extent, and when the downwardly directed force on the top E is released, the top E and arm 65 will return to but not above the predetermined point. Adjustment of the carriage 68 will predetermine the amount of 100 force downwardly on the top E which will be necessary to effect this downwardly yielding movement of the top section E.

The top section D is locked against rotation upon its center 29 when desired by 110 means of a bar 95 sliding endwise relative to and across the top of head F. Said bar is actuated by a pivoted hand lever 96, and has upwardly projecting lugs 97 and 98, one of which engages a notch 99 in one arm of 115 the frame 28, while the other engages under the opposite arm of frame 28, and in the locked position both serve to support the section D and to relieve the shaft 32 from strain.

My improved table is thus capable of being adjusted to secure a soft pliable flexible movement of the table section E, and adjustment thereof to correspond to the weight of the different patients. Said section has an endwise movement, a rocking movement and a pivotal movement, each of which may be locked or used independently of or in conjunction with the section E, and its separate adjustments employed inde- 120 125 130

pendently and locked when not required. All the table top sections are also supported upon and adjustable relative to a common standard or support which is itself vertically adjustable to secure the desired position of the patient vertically.

When the top section D is locked to the head F it becomes, in effect or for practical purposes, a part of the section C. When 10 the section D is unlocked from the head F and the forward or adjacent edge of section E is practically in engagement with the straight edge of section D, the sections D and E move in unison upon the shaft 6 as 15 a center practically as a single section, while when section D is free to move and section E is adjusted to leave a considerable gap between sections D and E each of the three sections are practically free and independent 20 of each other.

The mechanism herein illustrated and described is capable of considerable modification without departing from the principle of my invention.

25 Having described my invention, what I claim is:

1. A treatment table comprising a vertically adjustable standard, a main table top section mounted upon said standard, an oscillatable auxiliary table top section, and 30 means to support said auxiliary top section from said standard comprising a vertical axle journaled to said standard, a head carried rigidly by the upper end of said vertical axle above said standard and rotatably supported upon the upper face of said standard, a horizontal axle carried by said head, an oscillatable frame pivotally attached at one end to said horizontal axle, and 35 40 means to adjustably slidably connect said auxiliary top section to and above said oscillatable frame.

2. A treatment table comprising a vertically adjustable standard, a main table top section mounted upon said standard, an oscillatable auxiliary table top section, and 45 means to support said auxiliary top section comprising a vertical axle journaled to said standard, a head carried rigidly by said vertical axle above said standard and rotatably supported upon and above said standard, a horizontal axle carried by said head, an oscillatable frame pivotally attached at one 50 end to said horizontal axle and yieldingly supported in a substantially horizontal position, and means to adjustably slidably connect 55 said auxiliary top section to and above said oscillatable frame.

3. A treating table comprising a base, a 60 main table top section adjustable vertically and to different angles of inclination relative to said base, and an auxiliary table top section adjustable axially to and from said main top section and oscillatable trans- 65 versely to said adjustable axis, and means

to tension said oscillatory movement of the auxiliary top section.

4. A treating table comprising a base, a main table top section adjustable upon and relative to said base, and an auxiliary table 70 top section mounted upon said base and oscillatably adjustable relative to said base respectively upon vertical and horizontal axes, mechanism carried upon said base to yieldingly tension and restrain the respective 75 oscillatory movements of said auxiliary top section, and means to independently lock said auxiliary top section against oscillatory movement upon its respective axes of oscillation.

5. A treating table comprising a main table top section, an auxiliary table top section, a support common to both sections, means to rotatably oscillate said auxiliary top section upon a supporting axis parallel 85 to its longitudinal axis, and means to adjustably tension said oscillatory movement.

6. A treating table comprising a main table top section, an auxiliary table top section, a support common to both sections, 90 means to rotatably oscillate said auxiliary top section upon a supporting axis parallel to its longitudinal axis, and means to frictionally tension said oscillatory movement.

7. A treatment table comprising a stationary base, a vertically adjustable standard carried by said base, a main table top section mounted upon said standard, an oscillatable auxiliary table top section mounted upon said standard, and an intermediate 100 table top section mounted upon said standard and pivotally movable upon a vertical axis relative to said standard, and also adjustable to horizontal and inclined positions upon a horizontal axis relative to said standard, and means independent of the adjustments of said auxiliary table top section to lock said intermediate top section against movement upon its respective axes of adjustment.

8. A treatment table comprising a supporting member, a table top member pivotally supported relative to said supporting member and adjustable upon said support to different positions of inclination, a supporting rod to support said table top member in different positions of adjustment, said supporting rod being pivotally connected to said table top member and having sliding engagement with a recess in an automatically actuated locking member pivotally supported relative to said supporting member and adapted to engage and automatically lock said supporting rod against movement in one direction.

9. A treating table comprising a stationary base, a main table top section mounted upon said base, an intermediate table top section mounted upon said base, and an auxiliary table top section mounted upon 130

- 5 said base, said last named section being pivotally adjustable upon a plurality of axes arranged substantially at right angles to each other, mechanism to independently 5 tension the movements of said section upon its respective axes of adjustment, and means to independently lock said section against movement upon its respective axes of adjustment.
- 10 10. A treating table comprising a main table top section, an auxiliary table top section, said sections being supported relative to each other by means of a horizontally, pivotally supported frame, upon which said 15 last named section is mounted, and means to yieldingly and adjustably tension said pivotal frame comprising a second frame pivotally supported beneath said first frame and adjustably spaced therefrom at its free 20 end, and a spring having an adjustable point of engagement with said second frame and tending to elevate said second frame.
11. A treating table comprising a main table top section, an auxiliary table top section, a support for said top sections, and mechanism to yieldingly pivotally support said last mentioned section comprising a vertical shaft journaled to the support of said first mentioned section, frames pivotally connected to opposite ends of said 30 shaft, an adjustable brace connecting the free end of the lower frame to an intermediate point on the upper frame and a spring tending to force said lower frame upwardly.
- 35 12. A treating table comprising a standard, a main table top section, mounted upon said standard, an oscillatable auxiliary table top section, and means to support said auxiliary top section relative to said standard 40 comprising a frame pivoted upon a horizontal axis to said standard, cross-bars adjustable longitudinally upon said frame and pivotally connected to said auxiliary top section at right angles to the pivotal axis of 45 said frame to enable said auxiliary top section to be oscillated relative to said frame and upon said frame relative to said standard, and to be adjusted endwise relative to said frame.
- 50 13. A treating table comprising a supporting standard, a main table top section adjustably supported relative to said standard, an auxiliary table top section pivotally supported relative to said standard, a supporting 55 rod hinged to said main top section to support it in different positions of inclination, and a pivotally supported stirrup to automatically grip said supporting rod to lock said top section to its adjusted position, 60 and means to trip said stirrup to release said rod.
14. A treating table comprising a main table top section, a support therefor, an auxiliary table top section, and supporting 65 mechanism connecting said auxiliary top sec-
- tion to said support comprising a horizontally oscillating member pivotally connected to said support upon a vertical axis, a vertically oscillating frame pivotally connected upon a horizontal axis to said horizontally oscillating member, sliding members longitudinally adjustable upon said vertically oscillating frame, and brackets attached to said auxiliary top section and pivotally connected upon an axis longitudinally of said auxiliary top section to said sliding members, to enable said auxiliary top section to be oscillated relative to said support upon three axes at substantially right angles to each other and adjustable to and from said support.
15. A treating table comprising a main table top section, a support therefor, an auxiliary table top section pivotally connected to said support to oscillate vertically relative thereto, and mechanism to yieldingly support said auxiliary top section comprising substantially parallel pivotally mounted members, a member to adjustably space the free ends of said pivotally mounted members, and means connected to and adjustable longitudinally of one of said pivotally mounted members and tending to yieldingly elevate said pivotally mounted member.
16. A treating table comprising a stationary base, a standard mounted upon said base, a table top section to support the head and shoulders of a patient, mounted upon said standard, substantially parallel frames pivotally supported upon said standard and adjustably connected to transmit strain from one frame to the other, a spring tending to force one of said frames upwardly, and a table top section to support the lower extremities of a patient mounted upon one of said frames.
17. An operating table comprising a support; a main table section mounted on the support; a vertical post mounted on the support; auxiliary and intermediate table sections, each pivoted independently of the other on said post; and means locking the post against rotation on its longitudinal axis.
18. A main table section; an intermediate table section; an auxiliary table section; means permitting vertical adjustment of the intermediate table section; means permitting angular adjustment of the auxiliary table section relative to the plane of the main table top; and means for locking said auxiliary table section in said adjusted positions.
19. The combination in a table of the described character, of a main table section, intermediate table section and auxiliary table section, of supporting means for each of said table sections, means to adjust vertically and in unison the height of said main, 125
- 130

intermediate and auxiliary table sections, a friction clutch device for securing said table sections in their adjusted positions, and means for releasing said friction clutch device.

20. The combination in an osteopathic table, of a supporting pedestal and a main table-section carried thereby, a supporting shaft journaled in a branch of said pedestal, an auxiliary swinging leaf hingedly connected to the upper end of said shaft, a member extending approximately parallel with said auxiliary swinging leaf and being pivotally connected with the lower extremity 10 of said shaft, a link connection pivotally secured to the said auxiliary table-section and to the last said member, elastic means interposed between the table section and the said pivoted member extending parallel 15 therewith, and means for rigidly locking the said member and the auxiliary table-section in their adjusted position.

21. A main table section having supporting means, an auxiliary table section mov- 25 ably associated with said main table section, a supporting rod hinged to said main table section to support said main table section in different positions of inclination, and a pivotally supported locking member to automatically engage said supporting rod to lock 30 said main table section to its adjusted position.

22. A treatment table comprising a base, a standard vertically adjustable relative to 35 said base, a main table top section adjustably supported upon and relative to said stand-

ard, an auxiliary table top section oscillatably supported upon and relative to said standard, and members carried respectively by said base and standard having sliding engagement with each other and adapted to prevent rotative movement of said standard and table top sections relative to said base. 40

23. A treatment table comprising a stand- 45 ard, a main table top section mounted upon and relative to said standard, an auxiliary table top section mounted upon a substantially horizontal axle relative to said standard, an arm pivotally carried by said standard below said auxiliary top section, means to yieldingly lift said arm, a pair of telescopically connected supporting members respectively connected to said auxiliary top section and said arm to transmit a resilient support from said arm to said auxiliary top section, and a non-telescopic locking member adapted to be selectively employed in addition to said telescopic supporting members to support said auxiliary top section from said arm. 50 55

24. In a treatment table, a main table section, a resiliently sustained auxiliary table section oscillatable in a vertical direction, and means to be selectively employed to pre- 60 determine the upward limit of said oscillatory movement.

In testimony whereof I have affixed my signature in presence of two witnesses.
